UNITED STATES PATENT OFFICE.

JEROME C. TAFT, OF PROVIDENCE, RHODE ISLAND.

MANUFACTURE OF TWIST-DRILLS.

SPECIFICATION forming part of Letters Patent No. 430,792, dated June 24, 1890.

Application filed March 4, 1890. Serial No. 342,609. (No model.)

To all whom it may concern:

Be it known that I, JEROME C. TAFT, a citizen of the United States, residing at Providence, in the State of Rhode Island, have invented a new and useful Improvement in the Manufacture of Twist-Drills, of which the following is a specification.

My invention relates to the manufacture of twist-drills by first forming opposite longitudinal grooves in the drill-blank, and then twisting the same to spiral form; and my invention consists in first forming the opposite longitudinal clearing-grooves with opposite longitudinally flattened or depressed surfaces between them, then twisting the grooved blank to spiral form, and then compressing the metal at the cutting corner or edge of the grooves to improve the quality of the drill and reduce the same to a uniform diameter, as hereinafter fully set forth.

Figure 1 represents a side elevation of the drill-blank at a stage in the manufacture of the same at which the straight clearing-grooves and the intervening flattened or depressed surfaces have been formed. Fig. 2 represents an enlarged cross-section taken in the line xx of Fig. 1. Fig. 3 represents a subsequent stage in the manufacture at which the grooved drill-blank shown in Fig. 2 has been twisted so as to impart a spiral form to the clearing-grooves and intervening flattened or depressed surfaces. Fig. 4 represents an enlarged cross-section taken in the line xx of Fig. 3. Fig. 5 represents a side view of the finished drill provided with the compressed cutting corners or edges according to my improvement. Fig. 6 represents an enlarged cross-section taken in the line xx of Fig. 5.

In the accompanying drawings, A, Fig. 1, represents a drill-blank as heretofore em-

ployed in the manufacture of twist-drills, the said blank being provided with the straight longitudinal clearing-grooves aa and the intervening flattened or depressed surfaces bb , 45 as shown in the enlarged cross-section, Fig. 2, and A', Fig. 3, represents the drill-blank A when the same has been twisted so as to impart the required spiral form to the grooves aa and the intervening surfaces bb .

The twisting of the drill-blanks when of small and medium size is commonly performed without the application of heat, and in that case the metal at the cutting corners or edges cc of the clearing-grooves will 50 be deteriorated by the stretching tension to which it has been subjected in the operation of twisting; and it is the object of my improvement to restore the original quality of the metal at the said cutting-corners, and I 55 accomplish this result by compressing the said corners in suitable dies or between suitably-grooved rolls, whereby the metal at the cutting corner or edge c will be compacted, as shown in Fig. 6, thus improving the lasting 60 qualities of the cutting-corner of the drill, and at the same time reducing the drill to the proper standard size.

I claim as my invention—

The method of making twist-drills, which 70 consists in first providing the blank with opposite longitudinal clearing-grooves having opposite longitudinally flattened or depressed surfaces between them, then twisting the grooved blank to spiral form, and then compressing the metal at the cutting corner or 75 edge of the spiral grooves, as set forth.

JEROME C. TAFT.
